UNITED STATES PATENT OFFICE.

ORA E. SARR, OF SANDUSKY, OHIO.

ELECTRIC BOILER.

1,309,697.

Specification of Letters Patent. Patented July 15, 1919.

Application filed April 23, 1918. Serial No. 230,299.

To all whom it may concern:

Be it known that I, ORA E. SARR, a citizen of the United States, residing at Sandusky, in the county of Erie and State of Ohio, have invented a new and useful Electric Boiler, of which the following is a specification.

The present invention relates to an electrically heated boiler such as is used in connection with an engine, locomotive, turbine, or for steam heating purposes, and is applicable to any size and style boiler to whatever use or purpose it may be put.

A main object of the invention is the provision of electrical heating elements in conjunction with a boiler.

Another object of the invention is the provision of heating elements within a boiler which will occupy a large proportion 20 of the space within the boiler.

A still further object of the invention is the provision of means for incasing the heating elements.

Another object within the contemplation 25 of the invention is the provision of means for insulating the plates from their casings.

The invention also contemplates generally improving the construction and enhancing the utility of electrically heated 30 boilers.

With the foregoing and other objects in view which will appear as the description proceeds, the invention resides in the combination and arrangement of parts and in 35 the details of construction hereinafter described and claimed, it being understood that changes in the precise embodiment of the invention herein disclosed can be made within the scope of what is claimed without departing from the spirit of the invention.

A practical embodiment of the invention is shown in the accompanying drawings, wherein.

Figure 1 is a view in longitudinal section 45 of an ordinary horizontal boiler constructed in accordance with the invention;

Fig. 2 is a cross section of the same, the heating elements being in elevation with portions in section;

Fig. 3 is a view in side elevation of one 50 form of heating element or plate, the near side of the casing being cut away;

Fig. 4 is a cross section of the same;

Fig. 5 is an enlarged detail view partly 55 in elevation and partly in section of the electrical connection;

Fig. 6 is a view in perspective of a modified form of heating element, a portion being broken away;

Fig. 7 is a central transverse section of 60 the same;

Figs. 8, 9, 10, 11 and 12 are diagrammatic views showing different forms of wiring.

In the exterior firing of boilers, which is the most usual way of heating them, great 65 injury is often done the boiler shell and, even though great care be exercised, the material of the shell must deteriorate under the action of the fire and the gases rising therefrom.

By utilizing the electrical heating method and suspending the heating elements within the boiler and in contact with the water the resultant injury to the boiler shell is reduced to a minimum.

The heater is adapted for ready installation in any style boiler, whether the same be new or an old used boiler, and new life will be added to an old boiler by the installation of this heater because subsequent 80 injury to the boiler, due to external firing, will be eliminated.

Referring to the drawings by numerals of reference:

In carrying out the invention there is provided a boiler 10 which is herein shown as formed with a steam dome 11. It is to be understood that the steam dome is not a necessary part of a boiler heated in accordance with this invention as this heating system works as well on a boiler which has no steam dome as it does on one provided with a dome. The boiler may also be formed with an inlet 12 and an outlet or drain cock 13. One head of the boiler is formed with 95 a boss 14 which is apertured and countersunk to receive an insulating block 16, which is riveted or otherwise secured within the counter sunk portion of the aperture. Leads 16 pass through the insulating block 100 15 and to these are connected the exterior circuit wires or cables 17, in which circuit is interposed a switch 18 for the purpose of opening and closing the circuit. The interior circuit wires 19 are secured to the inner 105 terminals of the leads 16 for the purpose of conveying current to the heating elements.

Supporting bars 20 extend transversely of the interior of the boiler, to the shell of which they are secured in any suitable manner, and these bars are provided with a series of hangers spaced longitudinally there-

of, and herein shown as hooks 21. Depending from the hooks 21 are the insulating hangers 22 from which are suspended plates or heating elements indicated generally by 5 the numeral 23.

The plates 23 are formed of sheets 24 of suitable material offering sufficient resistance to the passage of an electrical current to cause them to become heated and so communicate heat to the water within the boiler, in which they are partially immersed. The 10 number of these plates will vary with the size of the boiler and with the conditions under which the boiler is to work, and it is contemplated using sufficient plates to take up considerable of the space within the 15 boiler and so diminish the liquid contents of the boiler.

While the plates 24 are herein shown as 20 inclosed in casings 25, it is to be understood that the plates may be installed without these casings when so desired, the plates having the same effect as heating elements with or without the casings.

The casings 25 are formed of sheet metal, preferably copper or galvanized iron, and are formed about the plates 24 completely inclosing the plates and their hangers or connectors 22'. These casings serve to 30 protect the plates 24 from the action of the water within the boiler and hence greatly enhance the efficiency of the plates. The upper edge of each casing 25 has castings or bosses 26 riveted or otherwise secured thereon, and 35 these bosses are centrally apertured to permit the passage therethrough of the interior circuit wires 19, which have electrical connection, as indicated by the numeral 27, with the plates 24. A consideration of Fig. 40 5 will render it apparent that the insulation of the wires 19 fits closely within and packs the apertures in the bosses 26 so that steam or water may not enter within the casing.

When desired, strips of asbestos 28 may 45 be placed on the plates 24 and separate the plates from the casings, as seen most clearly in Figs. 3 and 4. These asbestos strips are preferably of narrow width and are spaced apart and arranged longitudinally and 50 transversely of the plates. These strips, as will be understood, serve to keep the plates insulated from the casings.

In Figs. 6 and 7 a modified form of plate is shown, which is constructed of side plates 55 29, riveted or otherwise secured to the flanges 30 which extend outwardly from the peripheries of the rectangular frame 31, thus forming a hollow rectangular plate. In order that the plate so constructed may be 60 properly braced, crossed I-bars 32 are located within the plates and serve to protect the plate from strains tending to crush it. This plate has eyes 33 riveted or otherwise secured thereto to provide a means for hanging the plate.

It will be understood that the plate shown in Figs. 6 and 7 may also be inclosed in suitable sheet metal casing the same as the plates 24 hereinbefore described, if so desired.

The exterior wires or cables 17 are connected to any suitable source of electrical supply, not shown, for the purpose of conducting current to the cables 19 and plates 24. The plates 24 may be connected in circuit in a number of different ways, the principal ways in which it is desired to connect them being shown in Figs. 8 to 12, inclusive.

In Fig. 8 the cables 19 are shown as divided into a number of branch circuits equal 80 to the number of plates, and each plate is connected to form a part of one of these branch circuits.

In Fig. 9 is shown another form of connection wherein the cables 19 are divided to 85 form two branch circuits and half the plates are connected in one branch while the other half of the plates is connected in the second branch. In this instance the plates within a branch are so connected that the current 90 in adjoining plates flows in opposite directions.

By the connection shown in Fig. 10 the current flows through the plates in succession, the current entering the plate at one 95 side of the boiler and leaving the plate at the opposite side. The plates are so connected that the current will flow in opposite directions in adjoining plates.

In Fig. 11 is shown a method of connecting or wiring the plates wherein the cables 19 are divided into branch circuits equal to half the number of plates. Two plates are joined in each branch circuit, and the plates in a circuit are so connected that current 105 flows in opposite directions in the plates.

In Fig. 12 is shown another method of wiring the plates wherein the cables 19 are divided into branch circuits equal to half the number of plates. The plates are so 110 joined that current flows in one direction in all the plates at one side of the boiler, while current flows in the opposite direction in all the plates at the other side of the boiler.

Having thus described the invention, what 115 is claimed as new and sought by Letters Patent, is:—

1. A steam generator including a shell, insulating hangers mounted therein, and heating elements supported by the hangers 120 and spaced apart, each element including a casing, a plate within the casing adapted to be heated by an electric current directed thereto, and dielectric means interposed between the plate and casing for spacing them 125 apart, means connected to the plate for conducting electric current thereto, the current passing in one direction through some of the plates and in the opposite direction through the remaining plates.

2. In a device of the class described, the combination with a shell, and insulating hangers therein, of a plurality of spaced heating elements suspended from the hangers and within the shell, each element including a casing, a heating plate within the casing and spaced therefrom, dielectric means for holding each plate out of contact with its casing, each of said plates including 5 a frame and side plates secured to the frame to form a hollow member, said frame having intermediate crossed bars constituting braces, and means for conducting electrical

currents to the plates, said currents passing through the plates of some of the heating elements in one direction and through the remaining heating elements in the opposite direction.

In testimony that I claim the foregoing as my own, I have hereto affixed my signature in the presence of two witnesses.

ORA E. SARR.
